UNITED STATES PATENT OFFICE.

HOWARD S. HART, OF NEW BRITAIN, CONNECTICUT.

DESIGN FOR A TOP PLATE FOR REGISTERS, VENTILATORS, OR SIMILAR ARTICLES.

SPECIFICATION forming part of Design No. 35,583, dated January 14, 1902.

Application filed November 23, 1901. Serial No. 83,485. Term of patent 14 years.

To all whom it may concern:

Be it known that I, HOWARD S. HART, a citizen of the United States, residing at New Britain, county of Hartford, State of Connecticut, have invented and produced a new and original Design for a Top Plate for Registers, Ventilators, or Similar Articles, of which the following is a full, clear, and exact description.

My invention relates to a new and original design for top plates for registers, ventilators, or similar articles.

In the drawings, Figure 1 is a perspective view of a top plate embodying my design, and Fig. 2 is a cross-section on the plane of the line 1 1 of Fig. 1.

A is a plate. B B are holes therein. C C are connecting-bars conspicuously narrower than the width of the holes. The cross-section of the said bars C C is convex on the obverse side and concave on the reverse side. 20

What I claim is—

The design for a top plate for registers, ventilators or similar articles substantially as herein shown and described.

Signed at New Britain, Connecticut, this 25
20th day of November, 1901.

HOWARD S. HART.
